UNITED STATES PATENT OFFICE

GERALD SWALLOW, OF BRIDGEPORT, PENNSYLVANIA, ASSIGNOR, BY MESNE ASSIGNMENTS, TO CONTINENTAL-DIAMOND FIBRE COMPANY, OF NEWARK, DELAWARE, A CORPORATION OF DELAWARE

DUSTGUARD

Application filed May 5, 1928. Serial No. 275,357.

This invention relates to improvements in dust guards for the journals of railroad rolling stock, and the principal object of the invention is to provide a dust guard having characteristics which more generally fit it for the conditions under which it operates than the dust guards of prior manufacture.

More specifically, the invention contemplates the provision of a dust guard which shall be impervious to oil and grease, shall not split or fracture in use, which shall have flexibility sufficient to render it self-adjustable to the movements of the journal members, which shall be only slightly subject to frictional wear, and which shall form a snug fit with the axle and shall maintain such fit during extended periods of operation.

In the attached drawing:

Figure 1 is a longitudinal sectional view of a journal equipped with a dust guard made in accordance with my invention;

Fig. 2 is a section on the line 2-2, Fig. 1;

Figs. 3 and 4 are, respectively, perspective views illustrating two different embodiments of the invention;

Fig. 5 is a sectional view illustrating the manner in which the elements shown in Figs. 3 and 4 may be united to form a double guard, and

Figs. 6 and 7 are views in perspective of dust guards of modified form within the scope of the invention.

With particular reference to Figs. 1 and 2 of the drawing, it will be noted that the journal which may be of standard form comprises the usual journal box 1 at the outer end of which is pivotally mounted a cover 2 through which access is had to the interior of the box, and having its other or inner end open to admit the end of the axle 3. The axle has at its extremity a part 4 constituting the journal upon which bears the usual journal block 5 which supports the box 1 and the car body in the usual manner. At its inner end the box 1 is provided with a slotted recess 6 which intersects the opening 7 at the rear of the journal box through which the axle 3 projects, and this slot 6 is adapted for reception of a suitable dust guard which closely engages the axle and which excludes dust and

gritty material from the journal box in well known manner.

In the present instance and as shown in Fig. 3, the dust guard consists of a flat sheet 8 having transverse flanges 9, 9 at top and bottom and provided with an opening 10 through which the axle 3 extends and which conforms closely to the diameter of the part 3a of the axle so that the guard closely fits the axle and forms therewith a substantially tight dust-excluding joint. As shown in Figs. 1 and 2, the width of the guard 8 conforms closely to the width of the slot 6 which it occupies, while the flanges 9 are of such width as to fit neatly between the opposite walls of the slot, as clearly illustrated, so that the guard thus not only fits neatly around the journal but also fits snugly into the recess in the journal box provided for its reception. It will be noted that the flanges 9 function to hold the dust guard relatively fixed in the slot and also to stiffen and strengthen the guard as a whole.

I have discovered that vulcanized fibre is particularly well adapted for dust guard purposes, and that by forming the guard of vulcanized fibre, as illustrated, it possesses many desirable characteristics not found in guards as made in accordance with prior practice. Vulcanized fibre, as formed for example, by treating paper with zinc chloride solution and superimposing the treated sheets to form a laminated body of desired thickness, all in well known manner, is substantially impervious to oil and grease, and its physical characteristics are such that it will not split or fracture under normal operating conditions. Vulcanized fibre also is subject to very slight frictional wear, and the close fit between the guard and the axle journal will accordingly be maintained over long periods of use. A dust guard made as described, while having the necessary strength, still possesses sufficient flexibility to permit it to adjust itself readily to the relative movements between the axle and the journal box and thereby is not subject to wear and adverse strains to the same extent as an entirely rigid guard.

Obviously there may be considerable modi-

ification in the form of the dust guard without departure from the invention. By combining the guard shown in Fig. 3 for example with that shown in Fig. 4, a double guard such as illustrated in Fig. 5 will be formed. The guard shown in Fig. 3 has the outturned flanges only at top and bottom, whereas in that shown in Fig. 4, the flanges designated 11 are at the sides. By laying these two 10 guards together with the flanges turned inwardly, as shown in Fig. 5, a substantially closed casing is formed which will accurately fit the recess 6 in the journal box and through which the axle will extend in obvious manner. In this instance, there will be two joints 15 between the dust guard and the axle, one co-operating with the other to exclude dust from the bearing. In that form of guard shown in Fig. 1, the uppermost flange 9 closes the top of the recess 6, and this same flange functions in the device shown in Fig. 5 in the same manner.

A broader contact between the dust guard and the axle may be had in the form of device 25 shown in Fig. 6. In this instance, the dust guard is in all respects similar to the guard illustrated in Fig. 3, with the exception that there is provided around the opening 12 through which the axle projects a flange 13, 30 which in assembly closely surrounds the axle.

In the embodiment shown in Fig. 7, the device is provided with integral flanges 14, which in this instance project from all four sides of the device.

25 There may be still other modifications without departure from the invention.

I claim:

1. As an article of manufacture, a dust 40 guard for journal boxes having an opening at one end, an axle projecting into said box, said box having a transverse slot intersecting the aperture through which the shaft projects, said dust guard including a thin flexible non-metallic sheet adapted to abut one wall of the 45 slot, said sheet having at its upper and lower edges flanges adapted to extend between said wall of the slot and the opposed wall thereof and maintain the flanged edge portions of the sheet in contact with the first-named wall, the 50 sheet further having an opening for and of approximately the same diameter as the axle.

2. As an article of manufacture, a dust 55 guard for journal boxes having an opening at one end, an axle projecting into said box, said box having a transverse slot intersecting the aperture through which the shaft projects, said dust guard including a thin flexible non-metallic sheet adapted to abut one wall of the 60 slot, said sheet having at its upper and lower edges flanges adapted to extend between said wall of the slot and the opposed wall thereof and maintain the flanged edge portions of the sheet in contact with the first-named wall, the sheet further having an opening for and of 65 approximately the same diameter as the axle,

and a second sheet of similar material adapted to about the opposite wall of the slot and having at its side edges flanges to extend between said opposite wall and the first-named wall, said second sheet likewise having an 70 opening for the passage of and of substantially the same diameter as the axle.
